UNITED STATES PATENT OFFICE

154,744

DESIGN FOR AN AUTOMOBILE RADIATOR
GRILLE GUARD

Martin Browneye, Travis Helms, and George Tungett, Grand Rapids, Mich., assignors to Helms Industrial Development Company, Grand Rapids, Mich., a corporation of Michigan

Application October 4, 1948, Serial No. 148,954

Term of patent 14 years

(Cl. D14—6)

To all whom it may concern:

Be it known that we, Martin Browneye, Travis Helms and George Tungett, citizens of the United States, residing at Grand Rapids, in the county of Kent and State of Michigan, have invented a new, original, and ornamental Design for an Automobile Radiator Grille Guard, of which the following is a specification, reference being had to the accompanying drawing, forming part thereof.

Fig. 1 is a front angular perspective view of an automobile radiator grille guard showing our new design, and

Fig. 2 is a side elevation of the same.

We claim:

The ornamental design for an automobile radiator grille guard, substantially as shown.

MARTIN BROWNEYE.
TRAVIS HELMS.
GEORGE TUNGETT.
